(57) **CLAIM**

The ornamental design for a display screen or portion thereof with transitional graphical user interface of X-ray imaging device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with transitional graphical user interface of x-ray imaging device showing a first image according to the claimed design;

FIG. 2 is a front view of a display screen or portion thereof with transitional graphical user interface of x-ray imaging device showing a second image according to the claimed design;

FIG. 3 is a front view of a display screen or portion thereof with transitional graphical user interface of x-ray imaging device showing a third image according to the claimed design;

FIG. 4 is a front view of a display screen or portion thereof with transitional graphical user interface of x-ray imaging device showing a fourth image according to the claimed design;

FIG. 5 is a front view of a display screen or portion thereof with transitional graphical user interface of x-ray imaging device showing a fifth image according to the claimed design; and,

(Continued)

FIG. 6 is a front view of a display screen or portion thereof with transitional graphical user interface of x-ray imaging device showing a sixth image according to the claimed design.

The appearance of the transitional graphical user interface of x-ray imaging device transitions between the images shown in FIGS. 1-6. The process or period in which the transitional graphical user interface transitions forms no part of the claimed design. The broken line at the periphery of FIGS. 1-6 illustrates a display screen or portion thereof and forms no part of the claimed design. The interior dashed lines in a circular shape and triangular shape form part of the claim.
